CHRISTMAS TREE ORNAMENT OR SIMILAR ARTICLE

Jack Burnbaum, Newton, Mass., assignor, by direct and
mesne assignments, to Novelty Co., Inc., Cambridge,
Mass., a corporation

Filed Aug. 22, 1961, Ser. No. 66,451

Term of patent 14 years

(Cl. D29—1)

Fig. 1.

Fig. 4.

Fig. 3.

Fig. 2.

FIG. 1 is a top plan view of a Christmas tree ornament showing my new design;

FIG. 2 is a bottom plan view showing the clapper to one side;

FIG. 3 is a side elevational view thereof, and

FIG. 4 is an enlarged, segmental, perspective view of a portion of the main body of my ornament commencing at the bottom edge thereof.

The dominant features of the design reside in a series of conical sections or gores each bearing large and small flat facets progressively increasing in size from top to bottom, all as shown.

I claim:

The ornamental design for a Christmas tree ornament or similar article, substantially as shown and described.
